UNITED STATES PATENT OFFICE.

EDWARD A. JOHNSTON, OF CHICAGO, ILLINOIS, ASSIGNOR, BY MESNE ASSIGNMENTS,
TO INTERNATIONAL HARVESTER CORPORATION, A CORPORATION OF NEW JERSEY.

ENGINE-STARTING MECHANISM.

1,185,910.

Specification of Letters Patent.

Patented June 6, 1916.

Application filed April 1, 1912. Serial No. 687,837.

To all whom it may concern:

Be it known that I, EDWARD A. JOHNSTON, a citizen of the United States, residing at Chicago, in the county of Cook and State of Illinois, have invented certain new and useful Improvements in Engine-Starting Mechanism, of which the following is a specification.

My invention relates to mechanism where-
10 by an engine having a high horse power rat-
ing and comprising heavy operative parts
that require much power to move them from
a state of rest to one of motion, may be
given initial movement by a supplemental
15 and smaller engine that may be readily
connected therewith and disconnected there-
from, the means being adapted in particu-
lar for use in connection with the operation
of internal combustion engines of large di-
20 mensions wherein, in order to obtain an
explosive mixture in the power cylinder, or
cylinders, it is necessary, in starting the
same, to rotate the fly wheels thereof sev-
eral times by hand or other auxiliary power,
25 which is comparatively easy in operating
small engines, as but little power is re-
quired to impart the necessary initial revo-
lutions; but great difficulty is experienced
30 in starting engines with 25 to 50 horse
power; the object of my invention being to
provide means whereby an auxiliary engine
of small dimensions may be connected with
a larger engine in order to give initial move-
35 ment thereto and be quickly disconnected
when that object has been accomplished. I
attain these objects by means of the mecha-
nism illustrated by the accompanying draw-
ings, in which—

Figure 1 represents a plan view of part
40 of a large internal combustion engine hav-
ing a smaller engine mounted adjacent
thereto, and illustrating the manner of con-
necting it with the larger one; Fig. 2 is a
side elevation of Fig. 1; Fig. 3 is an end
45 elevation of Fig. 1. Fig. 4 is a detached de-
tail on an enlarged scale of part of the
means for connecting the small engine with
the larger one; and Fig. 5 is a side elevation
of Fig. 4.

50 Like reference characters designate the
same parts throughout the several views.

1 represents the power cylinder of a large
internal combustion engine, 2 the crank case
secured to a base frame including longi-
55 tudinally arranged sill members 3 designed

to form a part of the truck frame of a trac-
tion engine, 4 the crank shaft having a fly
wheel 5 secured to the end thereof, 6 repre-
sents a small internal combustion engine
having its power cylinder 7 and a crank 60
case 8 in one piece, and 9 represents an en-
gine supporting base plate that is secured
to the sill members 3 by means of bolts 10
and jaw members 11 engaging with the webs
of the sill members and the bottom of the 65
plate in a manner whereby the plate is ad-
justably secured to the upper side of the
truck frame members adjacent the periph-
ery of the fly wheel of the large engine.
The plate is provided at the end toward the 70
fly wheel with vertically arranged ear
members 12 that are spaced apart in a man-
ner to receive between them depending ear
members 13 integral with the bottom of the
crank case 8, and 14 represents a pin pass-
ing through openings in the ear members
and constituting a pivotal connection be-
tween the engine and plate whereby the en-
gine may be rocked about the axis thereof.

75 15 represents vertically arranged ear mem-
bers at the opposite end of the plate that
are provided with openings that receive a
transversely arranged rock shaft 16 pro-
vided with a hand crank 17 upon the outside
end thereof and with an enlarged head por-
tion 18 at the opposite end thereof, the
enlarged portion being arranged eccentric
80 to the axis of the shaft.

85 19 represents a laterally projecting boss
integral with the engine cylinder 7 directly
above the axis of shaft 16, and provided with
a horizontally arranged bore in which is
journaled a rocking stud 20, the head of the
stud being provided with a vertically ar-
ranged threaded opening that receives the
90 upper end of a connecting rod 21, and a cir-
cumferential groove 22 upon its bearing por-
tion adapted to receive the inner end of a set
screw 23 threaded in the boss, whereby the
stud is held against longitudinal movement
95 and permitted to rock about the axis thereof.

100 24 represents a split ring in which is jour-
naled the eccentric head 18 of the rock shaft
16, the ring being provided with ear members
25 upon opposite sides of the slotted opening
therein that receive a clamping screw 26 in
a manner whereby the ring may be caused
to closely engage the eccentric head 18.

110 27 represents a boss arranged upon the up-
per side of the ring and provided with a

threaded opening therein that receives the lower end of the connecting rod 21.

28 represents the crank shaft of the engine 6, having a fly wheel 29 secured to its inner 5 end, and a friction wheel 30 to its outer end that is adapted to engage with the periphery of the fly wheel 5 of the large engine when the small engine is rocked in one direction about the axis of pin 14. The crank shaft 10 28 extends beyond the friction wheel 30 and is adapted to receive a starting crank in any preferred manner. In operation, with the small engine adjusted upon the truck frame in a manner to bring the friction wheel, as 15 shown, in close proximity with the fly wheel 5, it is started, which may be easily accomplished, then the operator, by moving the hand crank 17 in the direction shown by the arrow in Fig. 2, rocks the small engine upward by means of the eccentric upon the rock shaft 16 and about the axis of the pin 14 in a manner whereby the friction wheel 30 is forced against the periphery of the fly wheel 5 and transmits motion thereto, which motion continues until the large engine receives power impulses in the usual way, and then the small engine is disconnected by a reverse movement of the crank 17. By having the small engine adjustable upon the truck 30 frame toward or from the fly wheel of the large engine, it may be moved thereon in a manner to compensate for wear of the friction wheel, and, by means of clamping screw 26, the ring 24 may be caused to engage with 35 the eccentric head 18 in a frictional manner sufficient to retain the wheel 30 in engagement with the fly wheel of the large engine without other securing means.

What I claim as my invention, and desire 40 to secure by Letters Patent, is:

1. A starting mechanism for internal combustion engines having, in combination, a

relatively small engine including a power cylinder, a crank case, a crank shaft journaled in bearings carried by said crank case, 45 a friction wheel secured to said crank shaft, a base plate, said crank case having a pivotal connection with said base plate, said base plate being supported adjacent a larger engine in a manner whereby said friction wheel 50 is in close proximity to the periphery of a fly wheel forming part of the larger engine, and means for rocking said small engine about the pivotal connection thereof with said base plate, said means including a 55 rock shaft journaled upon said base plate, said rock shaft having an enlarged portion eccentric to the axis thereof, a ring receiving said eccentric portion and a rod connecting said ring with said power cylinder whereby 60 a rocking movement of said shaft will raise or lower said cylinder and cause said friction wheel to move toward or from the periphery of a fly wheel forming part of the larger engine. 65

2. In combination, two engines having rotatable elements normally out of engagement with each other, one of said engines being pivotally mounted on and for starting the other engine, and rocking eccentric means 70 for moving said elements into engagement with each other for starting purposes.

3. In combination, two engines having rotatable elements normally out of engagement with each other, one of said engines 75 being movable with respect to the other and for starting said other engine, and eccentric means for moving one of said engines and also securing said elements into engagement with each other for starting purposes.

EDWARD A. JOHNSTON.
